(57) **CLAIM**

The ornamental design for a livestock head gate, as shown and described.

DESCRIPTION

FIG. 1 is a rear perspective view of a livestock head gate according to a first embodiment of the design.

FIG. 2 is a front perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is a rear perspective view of a livestock head gate according to a second embodiment of the design.

FIG. 10 is a front perspective view thereof;

FIG. 11 is a front elevational view thereof;

FIG. 12 is a rear elevational view thereof;

FIG. 13 is a left elevational view thereof;

FIG. 14 is a right elevational view thereof;

FIG. 15 is a top plan view thereof; and,

FIG. 16 is a bottom plan view thereof.

Broken lines illustrate portions of the article that form no part of the claimed design.
